UNITED STATES PATENT OFFICE.

MAURICE LEVISON, OF CHICAGO, ILLINOIS, ASSIGNOR TO CHICAGO SIGNAL COMPANY,
OF CHICAGO, ILLINOIS, A CORPORATION OF ILLINOIS.

CIRCUIT-CONTROLLING DEVICE.

1,157,012.

Specification of Letters Patent. Patented Oct. 19, 1915.

Application filed September 6, 1912. Serial No. 718,839.

To all whom it may concern:

Be it known that I, MAURICE LEVISON, a citizen of the United States, residing at Chicago, in the county of Cook and State 5 of Illinois, have invented certain new and useful Improvements in Circuit-Controlling Devices, of which the following is a specification.

My invention relates to improvements in 10 circuit-controlling devices, and more particularly to a device for connection in suitable circuits to actuate an annunciator upon continuous maintenance of certain conditions of a circuit for a predetermined lapse 15 of time.

Among the objects of my invention are to provide a simple, compact, and effective retard structure which may be built on a unit plan, so that a separate instrument may be 20 provided for each line; to provide advantageous means for adjusting the device to require greater or less lapse of time before actuating an annunciator; to provide in such construction means to prolong an annunciation, once started, until it is advisedly released, such means being independent of 25 the condition in the line which initially caused actuation of the annunciator; to provide such a structure which shall immediately return to normal upon restoration of 30 the primary circuit to normal condition before lapse of the predetermined time; and to provide for the manual release of a plurality of retard devices from annunciator- 35 operating position, either individually or as a whole, but without releasing those devices whose lines remain in actuating condition.

Other objects of my invention will become apparent to those skilled in the art 40 from a consideration of the following description, when taken in conjunction with the accompanying drawings, wherein—

Figure 1 is a front elevation of a device 45 embodying my invention; Fig. 2 is a plan view thereof; Fig. 3 is an enlarged section on line 3—3 of Fig. 2; Fig. 4 is an enlarged section on line 4—4 of Fig. 1; Fig. 5 is a diagrammatic view of the circuit connections of the device as applied to a hospital 50 signal system such as I have disclosed in my copending application, Serial No. 390,431, filed August 28, 1907; and Fig. 6

is a diagrammatic view of the circuit connections showing a modified application of the device.

The structure includes essentially an electro-responsive device for response to predetermined conditions in a main circuit, such device being herein shown as an electromagnet 10 suitably mounted upon base 55

11. The armature 12 of the electromagnet is arranged to close contacts and also to control the means by which an annunciation is to be effected after the predetermined lapse of time during all of which the electromagnet must be constantly energized. For convenience, the armature 12 may be 60 of L-shape, pivotally mounted as at 13 and retained in retracted position by spring 14. Coacting contacts 15—16 and 17—18 are 65 mounted upon insulating frame 19, said contacts standing normally open and adapted to be closed upon attraction of armature 12 by the electromagnet by means of pin 20 carried by the armature and provided with 70 insulating washers 21 engaging contacts 18 and 16 respectively.

Upon the end of the horizontal member of the armature 12 is mounted means whereby the armature may act, when attracted by the 80 electromagnet 10, to control mechanism through which the annunciation is caused to be actuated, and since, as hereafter to be described, the actuating means for the annunciator may conveniently include a 85 ratchet wheel, the armature-carried controlling means is shown as a "dead pawl" or holding pawl 22 pivotally mounted upon the armature as at 23 and yieldingly held to one limit of its movement by spring 24 90 which at one end engages the pawl and at the other end engages a post 25 carried by the armature, the pawl being of course provided with a stop portion 26 to limit the movement of the pawl by spring 24.

Devices are well known in the art for causing impulses in a circuit at regular timed intervals, and the mechanism for obtaining the timed operation of the annunciator-actuating means may therefore conveniently take the form of an electromagnet 100 30 for inclusion in a circuit in which the regular timed impulses occur, the electromagnet 30 being arranged to step up a

spring-returnable ratchet wheel which is to be held by the pawl 22 against spring return when, and only as long as, electromagnet 10 is energized. Specifically, 31 5 indicates the armature of the electromagnet 30 having pivotally mounted upon its end a pawl 32 having a slot 33 which engages, for slight lost motion, a guidepost 34, and 10 35 indicates a spring surrounding said post 34 and engaging the pawl 32 to press it downwardly toward the ratchet wheel to be described.

The annunciating devices may conveniently take the form of electric lamps and 15 the actuating means therefor involves contacts and a ratchet wheel to move the contacts, said wheel to be controlled by the electromagnets 10 and 30 respectively through the pawls 22 and 32. Specifically, 40, 41, 20 42, and 43 indicate contacts mounted in insulating frame 44, the contact spring 40 being longer than the other contacts and provided with a cross piece 45 so that in one 25 position the movable contact 40 co-operates with the single contact 41 and in another position the two contacts 42 and 43 coact with said cross piece of the movable contact 40.

The ratchet wheel heretofore mentioned 30 is indicated at 46 and is loosely mounted upon the supporting shaft 47 carried by the plate 11, a spring 48 being provided between the ratchet 46 and plate 11 to tend to rotate the ratchet backwardly or clockwise. 35 It will be seen that, since magnet 30 controls the "live" or active pawl for said ratchet and magnet 10 controls its "dead" or holding pawl, actuations of the electromagnet 30 will be ineffectual unless electromagnet 10 is energized to move the holding pawl 22 in coaction with the ratchet wheel.

49 indicates an insulating stud upon the front face of the ratchet wheel, the path of rotation of the stud 49 being intercepted by 45 the longer contact 40 so that the rotation of ratchet wheel 46 under operation of the electromagnets 10 and 30 as described will cause the stud 49 finally to strike the end of contact 40 and push it from coaction with contact 41 into coaction with contacts 42 and 43. It is desirable, however, that contact 41 should follow the central contact 40 almost until the latter engages contacts 42 and 43 and also that contact 40 be not forced so far toward the contacts 42 and 43 as to destroy the spring adjustment of the contacts 40, 42, and 43; the spring contact 41 is therefore appropriately resilient and the ratchet is stripped of one of its teeth, as 60 at 46', to be unable to advance the longer contact 40 past its switch-operating position.

I preferably provide means for varying the time interval which must elapse between

the instant of energization of electromagnet 10 and the final closure of the annunciator-controlling switch contacts. To this end, I provide an adjustable stop for defining the normal position of the switch-operating stud 49. 51 indicates such stop, 70 mounted on a disk 50 which is rotatably mounted on shaft 47 and retained thereon by nut 58. The disk carries a pointer sweeping over a graduated scale sector 52 rigidly mounted on the shaft 47, said pointer bearing a finger piece 57 by which it is moved. The pointer is in the form of a spring leaf pressing toward the dial and carrying a pin 56 for engagement in any selected one of a series of holes 53 in the dial, the holes being 80 spaced apart to correspond with the successive teeth on the ratchet. Thus with the pin 56 in the 5th hole the ratchet must make 5 steps to close the annunciator-controlling contacts, and so on.

85 A bar 59 is provided for supporting the binding posts for the device in obvious fashion.

I will now describe certain circuit arrangements in which the device above described may be very advantageously applied.

In Fig. 5 I have shown the application of a device to a hospital system, which, as described in my copending application above mentioned, includes a circuit extending from 95 battery 60 by wire 61 to an electromagnet 62, thence by wire 61' to the patient's normally open signal-initiating switch 63, and thence by wire 64 back to the battery, so that upon closing of the switch 63 the electromagnet 100 62 is energized. The armature of the electromagnet 62 is connected in circuit to light an annunciating lamp located at the nurse's cabinet and also to complete a holding circuit for the electromagnet 62 independent of 105 the patient's switch 63. Specifically the armature 65 of electromagnet 62 is connected as by wire 66 and return wire 64 to one terminal of the battery and upon attraction it is adapted to coact with contact 65' 110 which has parallel connection to the other terminal of the battery, on the one hand by wires 67 and 68 through an annunciating lamp 69 to wire 61 and on the other hand by wire 70 through a normally closed release switch 71 to wire 61' and thence back to battery through magnet 62. The release switch 71 is located at the patient's bedside so that the nurse may extinguish the light 69 and deenergize electromagnet 62 to cause retraction of armature 63 only by depressing the release switch 71 upon attending to the call. Armature 65 is also adapted to close contacts 72 and 73 and these are included in a battery circuit (61, 74, 75, 72, 73, 76, 10, 77, 120 64) with the electromagnet 10 of the device above described, so that manifestly, as soon as the patient presses call switch 63 closed

the switch 72-73 is closed and electromagnet 10 energized, so to remain until the nurse operates release switch 71 to release the annunciator 69 and show that the call has been answered. For the local circuits of the retard mechanism, I may run two battery wires 80 and 81 to wires 61 and 64 respectively, the former including a "common release" key 82 and the latter including the 10 clock 83 which closes the wire 81 at regular intervals,—say every half minute. Magnet 30 is controlled by switch 15-16, its circuit running by wire 82 to spring 40, contact 41, wire 84, switch 15-16, wire 85, magnet 30, 15 and wire 86, to clock wire 81. When contact 40 moves from point 41, it breaks the circuit for magnet 30 but closes two circuits, the one being an annunciator circuit extending from point 42 by wire 87 through annunciator 20 lamp 88 to wire 64, and the other being a holding circuit for magnet 10 extending from point 43 (connected through contact 40 with one side of battery) through wire 89, individual release key 90, and wire 91 to 25 wire 76 (thence through magnet 10 and wires 77-64 to complete the circuit to the other battery terminal). It will be observed that in this arrangement any number of the 30 devices may be included in circuit, the clock 83 being included in the common clock wire 81, the electromagnets 10 of the several devices having connection to the common feed wire 74 and return wire 64, a common release button 82 being included in a wire 80 35 to which the contacts 40 of the several devices are all connected, and the clock 83 being arranged in common wire 81 through which all electromagnets 30 receive current supply. In this way, the number of devices 40 may be multiplied indefinitely by connection of each thereof to the common wires as above described.

The operation of the device above described is as follows: Normally the contacts 45 all stand in the positions shown in Fig. 5, the circuits for all the electromagnets 10, 30, and 62 being broken. Now when a patient presses button 63, closing the circuit 60, 61, 62, 61', 63, 64, 60, electromagnet 62 is energized, attracting its armature 65 which contacts with the contact 65' and also closes the retard-controlling switch 72-73. The closing of the armature 65 against contact 65' closes parallel circuits from the armature 65 55 (which is connected by wires 66-64 to one terminal of the battery) through the nurse's lamp 69 on the one hand and the release circuit on the other, to the other terminal of the battery, the latter parallel circuit taking 60 the course 60, 61, 62, 61', 69, 70, 71, 67, 65', 65, 66, 64, 60, including the electromagnet 62 which is therefore locked in energized condition subject to deenergization only by the operation of release switch 71. In this position,—contacts 72-73 being closed,—electromagnet 10 is energized closing contacts 15-16 and moving pawl 22 into holding engagement with the ratchet wheel 46. The closure of contacts 15 and 16 completes the time-clock circuit for the electromagnet 30, 70 as follows: 60, 80, 82, 40, 41, 84, 15, 16, 85, 30, 86, 83, 81, 60. While this condition is maintained, each clock-controlled half-minute impulse energizes electromagnet 30, causing its pawl to dog the ratchet forward until, 75 after a number of impulses predetermined by adjustment of disk 50 and its stop pin 51, contact 40 is moved over to annunciator-operating position to close with its contacts 42-43. Once this position of switch closure 80 is attained, electromagnet 10 is thrown into holding circuit 60, 80, 82, 40, 43, 89, 90, 91, 10, 77, 64, 60, so that it can be released only by opening of either the common release key 82 or the individual release key 90. It will 85 be seen that if the nurse operates her release switch 71 before the predetermined time has elapsed, electromagnet 62 will be deenergized and its armature 65 retracted, so opening connection of contacts 73-72 and 90 deenergizing electromagnet 10, the retraction of armature 12 removing holding pawl 22 from engagement with ratchet wheel 46 and spring 48 acting to return the ratchet wheel 46 to normal position,—that is, to position where the stud 49 strikes the stop pin 51 in whatever position said stop pin is placed by operation of disk 50 and its pointer 54 over the sector 52. Therefore, if 95 the nurse answers the call before the lapse of the time predetermined by the setting of the stop pin, the superintendent's lamp 88 will not be lighted, but if she delays answering the call and operating the releasing switch 71 until that time has elapsed, the 100 device will operate, as described, to light the lamp 88 and throw electromagnet 10 into a holding circuit energized independently 105 of any circuit over which the nurse has control, so that the lamp 88 is not extinguished by any subsequent operation of the nurse's release switch 71. The superintendent, noting the lighting of the lamp 88, may break the holding circuit for electromagnet 10 by 110 operation of the release button 90, retraction of armature 12 removing the holding pawl 22 from ratchet wheel 46 and spring 48 returning the parts to normal. If desired 115 the release button 82 may be operated to break all of the holding circuits and return to normal all of those set devices for lines wherein the nurse's release switch 71 has been operated. Where the superintendent's signal is set but the nurse has not released the switch 71, electromagnet 62 is energized 120 and contacts 72-73 are still closed, so that under these conditions electromagnets 10 have energized circuits not affected by the

superintendent's release switch. Also, it will be noted, no device may be released until it has reached signal-setting position.

The arrangement above described and shown in Fig. 5 may be applied to a system already installed in accordance with the teachings of my copending application above mentioned, and in such installations the "maximum time" devices are advantageously installed in the supervisory station. By slightly modified wiring, however, the arrangement may be modified for elimination of some of the contacts and use of the electromagnet 10 to accomplish the work which, in the Fig. 5 arrangement, is done by electromagnet 62. Specifically, as shown in Fig. 6, electromagnet 10 is included in circuit with the patient's switch 63 (similarly to electromagnet 62 in the first described arrangement) and contacts 17 and 18 are arranged to be closed by the armature 12 of electromagnet 10 for establishing the parallel circuits from contact 17 (connected by wire 66 to one terminal of the battery) to contact 18 and wire 67 and thence in parallel by wire 68 to lamp 69 on the one hand, and on the other by wire 70 to the nurse's release switch 71, wire 61', electromagnet 10, wire 61 to battery, so holding the electromagnet 10 in energized condition pending operation of release switch 71. If said release switch 71 is operated obviously the electromagnet 10 will be deenergized and the parts returned to normal, but if the circuit is maintained by the release switch 71 for the predetermined time, the electromagnet 30 operates as heretofore described (the circuit being completed at 15—16 as before and extending from battery 60, over 81, 83, 86, 30, 95, 15, 16, 96, 97, 60). When contact 40 is moved into connection with contacts 42 and 43 parallel annunciator and holding circuits are established from contact 40 (connected to common wire 98 including general release switch 82) on the one hand through superintendent's lamp 88 to common wire 97 and on the other hand through release switch 90, wire 91, electromagnet 10, wire 61, and battery. Thus, the holding circuits may be released individually at 90 or as a whole at 82, as in the arrangement shown in Fig. 5. In this sort of an arrangement the maximum time switches are preferably placed in the nurse's annunciator cabinet, only the supervisory annunciators and release keys being located in the supervisory station.

The two diagrams which I have illustrated will show that the device described may be variously applied and it will be understood that structures embodying my invention may take forms adapting it to many other environments and that many changes in the structure herein described may be made without departing from the spirit of

the invention and within the scope of the appended claims, the particular adaptation to a hospital signal system being selected only to show one advantageous embodiment of the invention.

What I claim is:

1. Means for indicating maintenance of uniform circuit conditions for a predetermined time comprising, in combination, a circuit, the closure whereof is to be indicated, an electro-responsive device therein, a self restoring movable part restrainable against restoration during and by the energization of said electro-responsive device, means to move said movable part at a known rate, signaling means operable by said movable part after predetermined movement for indication of the continuous closure of said circuit for the predetermined time, and means operated by said movable part to maintain the signal in operation regardless of subsequent deenergization of the said circuit.

2. In a device of the character described, an electro-responsive device, for connection in a circuit, a self restoring movable part restrainable against restoration during and by the energization of said electro-responsive device, means to move said movable part at a known rate, holding means for said movable part and signaling means, both operable by said movable part after a predetermined movement, whereby the signal once operated is maintained in operation.

3. In a device of the character described, an electro-responsive device, a self restoring movable part restrainable against restoration during and by the energization of said electro-responsive device, means to hold said movable part, and signaling means, both operable in response to actuation by said movable part after a predetermined movement, means to release said holding means, and means to vary said predetermined movement of said part necessary for operation of said signaling means and holding means.

4. In a device of the character described, an electro-responsive device, contacts for controlling a signal circuit, and means to operate said contacts including a movable part, timed means for moving said movable part intermittently, means associated with said movable part for operation of said contacts after a predetermined number of effective intermittent movements of the movable part, means responsive to energization of the electro-responsive device for rendering effective said movements of the movable part, means automatically to maintain said contacts closed, and manual releasing means therefor.

5. In a device of the character described, an electro-responsive device, means to energize it, a holding circuit for said electro-re-

- responsive device, an annunciator circuit, contacts for controlling the holding circuit for the electro-responsive device and the annunciator circuit, and means to operate said contacts including a part movable from normal position, timed means for moving said part from normal position toward contact-operating position, and means responsive to energization of said electro-responsive device to prevent return of said movable part to normal position during continuance of the energization of said electro-responsive device.
6. In a device of the character described, an electro-responsive device, means to energize it, a step-up wheel, a holding pawl therefor controlled by said electro-responsive device and rendered operative by the energization of the latter, an active pawl for said step-up device, an electromagnet for operating said pawl, a circuit for said electromagnet controlled by said electroresponsive device, means in said circuit for occasioning electrical impulses therein at regular intervals, a holding circuit for said electroresponsive device, normally open, a normally open signal circuit, and means controlled by said step-up device for closing the last two said circuits after a predetermined number of operations of said electromagnet.
7. In a device of the character described, an electro-responsive device, means to energize it, a holding circuit for said electro-responsive device, an annunciator circuit, contacts for controlling the holding circuit for the electro-responsive device and the annunciator circuit, means to operate said contacts including a part movable from normal position, timed means for moving said part from normal position toward contact operating position, and means responsive to energization of said electro-responsive device to prevent return of said movable part to normal position during continuance of the energization of said electro-responsive device, and a manual switch for opening said holding circuit.
8. The combination of an electro-responsive device, means at a signaling station to close a circuit therefor, a normally closed switch at said signaling station, means including said switch for maintaining a circuit for said electroresponsive device subject to interruption by the opening of said switch, a signal, means controlled by said electro-responsive device to actuate said signal upon maintenance of said electro-responsive device in energized condition for a predetermined time, means automatically to maintain said signal when set, regardless of opening of the normally closed switch, and signal releasing means at a supervisory station.
9. In a device of the character described, an electro-magnet 10, an electro-magnet 30, 65 a step-up wheel having an active pawl controlled by the armature of magnet 30 and a holding pawl controlled by the armature of magnet 10, means to energize the magnet 10, means controlled by magnet 10 for energizing magnet 30 at regular time intervals, a signal, a normally open circuit therefor, a normally open holding circuit for magnet 10, and means for closing said circuits controlled by predetermined movement of the 75 step-up wheel.
10. In a device of the character described, a frame, a shaft thereon, a self-restoring ratchet wheel on the shaft, electric contacts to be closed by rotation of the wheel through 80 a predetermined arc, fixed in their relation to the ratchet wheel, means on the ratchet wheel to operate said contacts, a fixed dial, an indicator on the shaft rotatable to different positions indicated on said dial, means 85 for fixing said rotatable part in relation to the dial, a stop carried by said rotatable part for determining the extent of return movement of the ratchet wheel to define the initial position of the ratchet wheel, electro-responsive means for advancing said ratchet wheel and electro-responsive means for holding said ratchet wheel against self restoration.
11. In a device of the character described, 95 a frame, two electromagnets mounted thereon, a self-restoring ratchet wheel mounted on the frame between said electromagnets, a holding pawl for the ratchet wheel carried by the armature of one electro-magnet inoperative when retracted, an active pawl carried by the armature of the other electromagnet, and means for operation by the ratchet upon predetermined rotation thereof of controlling the magnet for the holding 100 pawl to cause deenergization thereof.
12. In a device of the character described, a frame, a self-restoring ratchet wheel carrying a contact-operating stud, electromagnets, 110 pawls operable thereby respectively for holding and stepping up said ratchet wheel, and an adjustable part provided with an abutment for the ratchet wheel adjustably to define its initial position.
13. In a device of the character described, 115 a frame, a shaft carried thereby, a self-restoring ratchet thereon, electromagnets respectively to hold and step-up said ratchet wheel, a dial member fixedly carried by the shaft, a rotatable member carried by the shaft, a pointer on said rotatable member co-acting with the dial, an abutment on the rotatable member defining the initial position of the ratchet wheel, and means operable by the ratchet upon movement thereof from the 120 position defined by said adjustable abutment.
14. In a device of the character described,

a frame, a shaft thereon, a self-restoring ratchet wheel on the shaft, means for operation by the ratchet, a pin on the ratchet to operate said means, a rotatably adjustable part on the shaft, a stud on said part for coaction with said ratchet-carried pin, to define the initial position of the ratchet, and means to hold against self-restoration and

to step-up said ratchet from said initial position so defined to operating position.

In testimony whereof I hereunto set my hand in the presence of two witnesses.

MAURICE LEVISON.

In the presence of—

MARY F. ALLEN,

W. LINN ALLEN.
